LOCK CONSTRUCTION

Charles Courtney, New York, N. Y.

Application February 23, 1935, Serial No. 7,699

20 Claims. (Cl. 70—131)

This invention relates to lock construction.

One of the objects of this invention is to provide a simple, inexpensive and thoroughly practical lock construction. Another object is to provide a construction of the above nature characterized by adaptability and versatility. Another object is to provide a bolt operating mechanism comprised of but few simple and inexpensive parts which may be rapidly manufactured and readily assembled. Another object is to provide a mechanism of the above character which is sturdy and durable and the direction of operation of which is reversible. Another object is to provide a construction of the above nature capable of indicating audibly and visibly improper manipulation, as for example, the forcing of the lock. Other objects will be in part apparent and in part pointed out hereinafter.

The invention accordingly consists in the features of construction, combinations of elements and arrangement of parts as will be exemplified in the structure to be hereinafter described and the scope of the application of which will be indicated in the following claims.

25 In the accompanying drawings, in which is shown a preferred embodiment of my invention,

Figure 1 is a front elevation on a smaller scale of my lock secured to a door, the bolt mechanism being indicated in a dotted line position;

30 Figure 2 is a rear elevation of my lock installed on a door, certain parts of the lock casing being broken away to show the bolt mechanism;

Figure 3 is a sectional view taken along line 3—3 of Figure 2;

35 Figure 4 is a side elevation partly in section and partly broken away to show certain of the operating elements;

Figure 5 is a rear elevation taken along the line 5—5 of Figure 4;

40 Figure 6 is a rear elevation taken along the line 6—6 of Figure 4.

Similar reference characters refer to similar parts throughout the various views of the drawings.

45 Referring first to Figure 1, a door 10 or the like has mounted thereon a front face plate 11 through which extends a door knob 12 and other bolt or latch operating parts. As is more clearly shown in Figure 3, a door jamb 13 limits the swing of door 10 which, when in its closed position, registers with a wall or partition 13a to which the door is to be locked.

A suitable key-controlled mechanism 15 (Figure 3) is so related to the door as to be accessible from the outside face thereof. Mechanism 15

may have an escutcheon plate 14 abutting face plate 11, mechanism 15 being received in a hole 19a in door 10, and being secured to front face plate 11 by a pair of screws 16 threaded through a pair of bosses 17 integrally formed with the 5 housing of mechanism 15. Screws 16 preferably force a U-shaped plate 18 (Figure 5) against the rear of front face plate 11 (Figure 3) to clamp escutcheon plate 14 against front plate 11 and thus secure mechanism 15 in place.

10 As is more clearly shown in Figures 2, 3, 4 and 5, a rear plate 19 is held in assembled relation with door 10 and front plate 11 by a suitable number of screws 20 (Figure 2 or 5) extending through rear plate 19 and preferably threaded into a like 15 number of posts 21 (Figure 4) extending through door 10, posts 21 being secured at their other ends to front plate 11. Thus, front plate 11 and rear plate 19 are clamped against opposite sides of door 10 in such a manner as to effectively support the various operating members of the lock.

20 Referring again to Figures 2 and 3, a pair of substantially rectangular plates 22 are secured as by rivets or the like (not shown) to rear plate 19 and have extending therefrom projections 23 25 (better shown in Figure 2) having threaded holes 23a extending therethrough. A suitable casing 24 (Figure 3) fits over and is secured to projections 23 by suitable screws 25 threaded into holes 23a to form a chamber 26 in which a 30 bolt, generally indicated at 27, is slidably disposed.

When door 10 is in its closed position, as better shown in Figure 3, chamber 26 and keeper 28 have respective registering openings 26a and 28a 35 through which bolt 27 projects when it is operated to lock door 10 in its closed position.

40 Bolt 27 preferably comprises a pair of parallel spaced plates 29 and 30 (Figure 3) which are held apart by a spacing bar 31 at the left hand end (Figure 3) and by superimposed spacing plates 33 at the right hand end. Suitable rivets 34 or the like extend through the plates and spacers to secure the several parts together as a unit. There is thus formed a space between 45 the plates 29 and 30 for a purpose later set forth.

45 Spacing plates 32 and 33 preferably have associated therewith an extending lug or stop 35 (Figure 2) adapted to limit the travel of bolt 27 in bolt retracting direction by abutting against projection 23 when bolt 27 is withdrawn from its locked position. Preferably stop 35 has a recess 35a to provide a clearance for the end of screw 25 when stop 35 abuts projection 23. Stop or lug 35 also has formed on the other or left hand 55

side thereof a cam recess 35b, the purpose of which will be described hereinafter.

Disposed between plates 29 and 30 and thus within the hollow of bolt 27 is a part generally indicated at 36, being pivoted as by a pin 37 carried by plates 29 and 30 (Figure 2). Part 36 preferably has suitable projections comprising an actuating arm 36a, a stop arm 36b, a locking arm 36c and a cam cavity 36d, the purpose of which 10 will be pointed out hereinafter, and the part conveniently having, therefore, a shape like that shown in Figure 2. A part, generally indicated at 38 (Figure 2), is mounted to pivot about the axis of a pin 39 bridged across the space between plates 29 and 30, and comprises a stop arm 38a, a cam portion 38b, a cam portion 38c and a locking arm 38d, the purpose of which will be pointed out hereinafter, part 38 thus having a shape like that shown in Figure 2.

Preferably, plates 29 and 30 are provided with openings 29a (Figure 2) and 30a (Figure 3), having extensions or recesses 29b and 30b respectively, these openings in the two plates being similar in shape. Thus arm 36a of part 36 lies between 25 and is accessible through recesses 29b and 30b so that a projection or crank pin 40 (Figure 2) normally extending through opening 30a of part 30 will, when moved into recess or opening 29b, abut against arm 36a to swing part 36 in counter-clockwise direction, as viewed in Figure 2. As 30 part 38 swings, it imparts clockwise rotation to part 36 because of the coaction of cam cavity 36d and cam portion 38c, thus causing the locking arms 36c and 38d (projecting from the upper and lower sides of bolt as viewed in Figure 2) to recede or be withdrawn into the space between plates 29 and 30, into the bolt 27, and thus moved out of engagement with the inside wall of keeper 28, hence conditioning bolt 27 for withdrawal or retraction from keeper 28 upon further movement of crank pin 40 in clockwise direction as viewed in Figure 1.

A pair of lugs 29c and 30c (Figures 2 and 4) project (lower right-hand part of Figure 2) from plates 29 and 30 and have pivotally mounted therebetween, as by a pin 41e, a lever generally indicated at 41 having an end portion 41a extending toward the left (Figure 2) and bearing against cam 38b on part 38. Lever 41 conveniently takes the form of a bell crank lever and its other arm 41b suitably receives one end of a spring 42, the other end of which is secured to arm 38a of part 38 whereby spring 42 biases lock arm 38d and consequently lock arm 36c into their 55 extended or locking position in relation to or in back of the wall of keeper 28, as illustratively shown in Figure 2.

Arm 41a, at its extreme left end (Figure 2), acts as a stop to limit the extent to which the parts 36 and 38 are swung or held in clockwise and counterclockwise directions, respectively, about their pivots 37 and 39, and hence also the extent to which the lock arms 36c and 38d are projected out of the bolt 27.

Preferably, I provide a lug 41c, on lever 41 (Figure 2) to retain bolt 27 in its locked or unlocked position, and this, by a coaction with a lug or stop-like projection 43 (Figures 2 and 4) extending at right angles from plate 44, which is 70 suitably secured to plate 19. Thus, when parts 36 and 38 are swung against the bias of spring 42, cam 38b bears against end portion or arm 41a of lever 41, forcing lug 41c away from bolt 27 to permit lug 41c to pass projection 43 as the bolt 75 is moved, lug 41c thus riding into a position at

one or the other side of the fixed abutment or projection 43, depending upon whether bolt 27 is projected or withdrawn, thereby blocking further movement by bolt 27 and holding it in either projected or withdrawn position. Thus, upon 5 completion of withdrawal of the bolt 27 into the casing, the detent lug 41c becomes positioned to the right of the fixed abutment 43 and these parts thus hold the bolt against movement in projecting direction; however, upon completion 10 of projecting movement of the bolt 27 and into the relationship shown in Figure 2, the detent lug 41c becomes positioned to the left of the abutment 43 and holds the bolt against movement in the direction of withdrawing it into the casing. 15 In this latter relationship of the parts, however, and as is best shown in Figure 2, another lug or projecting portion 41d of the lever 41 becomes positioned to the right of the fixed abutment 43 but spaced therefrom by an appropriate distance of 20 the order indicated in Figure 2; thereby, and for purposes later pointed out, the bolt 27 may partake of an additional movement in projecting direction (toward the left as viewed in Figure 2) by an amount corresponding to the above-men- 25 tioned distance or spacing between the parts 43 and 41d. In this latter connection, it will be noted, also, that, with the bolt normally projected as shown in Figure 2, the stop arms 36b and 38a of the members 36 and 38 assume positions spaced somewhat to the right of the left-hand casing parts, such as the parts 23, 23, thereby also permitting the above-mentioned additional movement of the bolt in bolt-projecting direction, but positively precluding a complete 30 movement of the bolt 27 entirely out of the casing. 35

Preferably, means are provided for operating bolt 27 from either side of door 10. Accordingly, an operating bar 15a is secured to the key-rotated plug 15b (Figures 1 and 3) of the key mechanism 15 and is rotatable therewith. Bar 15a extends into a slot 47 formed in a bushing 48 rotatably carried by rear plate 19 in a hole 19a extending therethrough. 45

Secured to bushing 48 is a crank disk 49 (Figure 3) which carries crank pin 40, and, as already described above, crank pin 40 actuates, in coaction with the spring 42, arm 36a as it enters or leaves recess 30b in plate 30. Thus, when the proper key is inserted into plug 15b and turned, bar 15a rotates disk 49 (clockwise, in Figure 2) which in turn brings crank pin 40 to bear against arm 36a of part 36. Parts 36 and 38 are thus swung in opposite directions, against action of spring 42, to withdraw locking arms 36c and 38d from the back of the wall of keeper 28, crank pin 40 entering the plate recess 30b and the swinging of part 38 causing cam 38b to force lever 41 away from the bolt to permit the passage of lug or 55 detent 41c past projection 43. 60

As crank disk 49 continues to rotate (clockwise, Figure 2), crank pin 40 thereon, having entered recess 30b in bolt 27, bears against the right-hand wall of recess 30b (as viewed in Figure 2) to force and move bolt 27 to the right until stop lugs 35 thereon abut projection 23. Just before this point is reached, however, crank pin 40 rotates out of recess 30b, thus releasing arm 36a and accordingly parts 36 and 38. Hence, due to 70 the bias of spring 42, lock arms 36c and 38d are again projected out from the space between plates 29 and 30 of the bolt 27, but by now they and the bolt are withdrawn into the casing so that their lateral projection from the bolt takes place inside 75

the casing, not inside the keeper 28; and lever 41 is released and shifted so that lug 41c now lies to the right (instead of to the left) of projection 43 and acts as a stop against a casual or unintentional throwing of the bolt.

Thus, the bolt-withdrawing operation, as controlled by a key from the exterior of the door, is concluded. To project the bolt structure into door locking position the key-controlled mechanism, and accordingly the crank pin 40, is rotated in reverse direction, thus bringing about a reverse sequence of the operations just described.

It may now be seen that a double locking engagement is established between casing 24 and keeper 28. Inasmuch as bolt 27 extends through openings 28a and 26a of the keeper and casing respectively, swinging of door 10 is restrained, and as locking arms 36c and 38d extend beyond the limits of opening 28a and in back of and along the inside of the wall of keeper 28, bolt 27 is held against retraction.

To permit the operation of the bolt from the inner side of door 10 I preferably provide a suitable handle 50 or the like (Figures 3 and 4) mounted on a disk 51 bearing against the top of casing 24. A shaft 52 secured to handle 50 is rotatably received through a hole 24a in casing 24 and has secured to the lower end thereof (Figure 3) a disk 53 from which extends a pair of projections forming crank pins 54 and 55. Two inwardly projecting pins 56 are secured to the top wall of casing 24 (Figure 3) and extend rearwardly through oppositely disposed holes in a washer 57 and a resilient washer 58. Resilient washer 58 acts as a spring to force washer 57 against disk 53, thus creating a friction therebetween.

As is more clearly shown in Figure 4, two shallow depressions 53a and 53b are provided in disk 53 and into these depressions pins 56 drop when registering therewith, thus determining the position of handle 50 in either of its two extremities of rotary movement.

When handle 50 is rotated crank pin 55 enters recess 29b of bolt plate 29 (Figure 2) and also bears against arm 36a, as pointed out above with respect to crank pin 40, and operates the bolt in substantially similar manner. As crank pins 54 and 55 are in no way connected with crank pin 40, the bolt can be operated by either without interference therebetween.

Under certain conditions I have found it preferable to provide an audible and a visible signal to indicate an improper or illegal or attempted operation of the lock. Illustratively, I provide an audible signal, as for example a mechanically or spring-operated bell generally indicated at 60 (Figures 2, 4 and 6). As is more clearly shown in Figure 4, bell 60 is preferably received in a hole 10a of door 10 and is secured to front plate 11, bell 60 and its operating parts being covered by rear plate 19. As is more clearly shown in Figures 4 and 6, bell 60 includes a casing 61 which houses a coiled spring (not shown) which, when released, actuates a train of gears generally indicated at 62 (Figure 5).

Gear train 62 is held inoperative preferably by a double-toothed detent or escapement 63 to which is attached a resilient bar or spring 64, which at one end of which is mounted a clapper 65. A detent 63 is pivotally mounted on a pin 63a secured to the top of casing 61 and has an arm 63b normally retained against movement by a spring-biased stop 79, as pointed out hereinafter.

When arm 63b is free to move, escapement 63 is

also free to pivot, which it does under the influence of gear train 62 and its actuating spring. Thus, release of arm 63b releases the gear train and the coil spring and a rapid pivotal reciprocation is imparted to escapement 63, which in turn is imparted to clapper 65 against a gong 66 of bell 60.

As mentioned above, bell 60 is not sounded unless the lock has been improperly tampered with, as for example when it is being attempted to be forced by a burglar or the like. Thus, if bolt 27 is being improperly forced, as by the insertion of a tool such as a jimmy, between door 10 and door frame 13a (Figures 1, 2 and 3), there results a separating movement between keeper 15 28 and lock casing 24, thus bringing about a relative movement therebetween in bolt-projecting direction and causing lock arms 36c and 38d to take in back of the keeper wall, also a movement between bolt 27 and its casing 24. Bolt 27 is 20 hence displaced to the left of the position shown in Figure 2 so that cam portion 35b on stop 35 bears against a lug 67a (Figures 2 and 4), which projects at right angles from a plate 67 mounted on a tubular shaft 68 (Figure 4) secured to a 25 bushing 69 pivotally mounted in rear plate 19, as is more clearly shown in Figure 4.

As is better shown in Figure 2, plate 67 has an arcuate slot 67b therein, through which extends a pin 70 secured to rear plate 19. A lug 67c extends from plate 67 and is embraced by the ends of a spring 71, the body of which is preferably wound about hollow shaft 68 (Figures 2 and 4). Thus, spring 71 constantly biases plate 67 against displacement from its neutral position.

As is more clearly shown in Figure 4, bushing 69 has a square bore 69a which slidably receives a square bar 72, the end of which is seated in and secured to a bushing 73 rotatably mounted in a bore 74 in plate 11. An eccentric or double acting cam 75 is mounted on bar 72 to be rotatable therewith to bear against and cause linear translation or up and down movement of a part 76 (Figure 5) toward or away from the bell 60, part 76 and eccentric 75 being held in position against 45 the rear surface of front plate 11 by a plate 77 and a screw 78 threaded into front plate 11. Part 76 is plate-like and is vertically slotted (see Figures 4, 5 and 6) so that it may move up and down relative to the screw 78. It has an arm-like extension 76a which, when part 76 is raised, abuts against and lifts a spring-biased stop 79 (Figure 5) up and away from arm 63b of escapement detent 63, thereby to free the latter.

Thus, when cam 35 bears against lug 67a (Figure 2), plate 67 is turned, this rotation being translated into a linear or upward travel of part 76 (Figure 4) by means of bushing 69 turning shaft or bar 72, which in turn swings or rotates cam 75 to lift plate 76. Arm 76a of part 76 lifts 50 the spring-biased stop 79 (Figure 5), which holds escapement 63 stationary (Figure 5), thereby releasing the escapement mechanism and the energy of the spring motor effects a ringing of the bell as described above and accordingly gives 55 audible notice of the improper operation of the lock. Thus, a marauder or burglar having his work thus accompanied by a loud bell ringing over which he has no control, quickly ceases his nefarious operation.

Preferably I provide a knob 89 (Figure 4) secured to a preferably hollow shaft 81 rotatably mounted in bearing 19b formed on rear plate 19. A key bar 82 is connected to the coil spring in bell 60 and to shaft 81. Thus, rotation of 75

knob 80 winds up the spring for actuation of bell 60 so that the latter may be maintained in condition for proper signaling.

As pointed out above, I preferably provide a visible signal in addition to the audible signal already described. As is more clearly shown in Figures 4, 5 and 6, a tubular shaft 83 is pivotally mounted upon a stud 84 having an end 84a threaded into front plate 11. Shaft 83 has formed on one end thereof a projection or arm 85 which bears against an edge 76b of part 76 (Figures 5 and 6). Thus, when motion is imparted to part 76, as pointed out above, arm 85 is forced away from the line of travel of part 76, thus causing the pivoting of shaft 83. As shaft 83 pivots an arm 86 preferably secured to the other end of shaft 83 swings. Pivotaly mounted on the free or upper end of arm 86 is a catch 87 having a sloping face 87a. A spring 88 secured to arm 86 by pins 89 or the like constantly biases catch 87 in a clockwise direction.

A flag 90 having a colored portion 90a is mounted on a shaft 91 (Figures 4 and 6) pivotally received in a suitable bearing in rear plate 19, the latter having an aperture 19c (Figure 2) normally closed by the uncolored portion of the flag 90. Flag 90 tends by its weight to swing counter-clockwise as viewed in Figures 2 and 6 toward and against a stop pin 94 projecting inwardly (Figures 4 and 6) from the wall plate 19. A loop or catch 90b (Figure 6) is preferably integrally formed with flag 90 and catches under the tongue 87b on catch 87 and holds flag 90 in non-signaling position. Thus, when arm 86 is swung as pointed out above, projection 87b is swung (to the left in Figure 6) away from catch 90b and flag 90 is permitted to drop, whereby colored portion 90a becomes visible through hole 19c (Figure 2) in rear plate 19 to indicate that an attempt has been or is being made to force the lock. The signal thus also indicates that the spring of the bell mechanism may require rewinding.

To restore flag 90 to its non-indicating position I preferably provide a knob 92 on a shaft 91 (Figure 4). When knob 92 is turned in a clockwise direction (Figures 2 and 4) flag 90 is raised, causing loop 90b to bear against sloping edge 87a (Figure 6) and causing catch 87 to pivot against the bias of spring 88. When the bottom of latch or tongue 87b registers with the top of loop 90b, catch 87 snaps to the right and over the top of loop 90b and thus holds flag 90 in a raised position. Preferably, I provide a pair of stop pins 93 (Figure 6) secured to rear plate 19 to limit the swing of arm 86 in one direction, shaft 91 acting to limit its swing in the other direction, and thus I insure that arm 86 will not swing so far in either direction as to escape the action of loop 90b when the flag is returned by knob 92 to its raised or non-indicating position.

However, another coacting feature of my invention comes into play in response to an attempted forcing of the lock. I have already above described in detail how, referring now to Figure 2, any attempt to jimmy the lock or force the keeper 23 and the door or lock casing 24 apart results in a separating movement in a direction toward the left, as viewed in Figure 2, of the opposite or built-up bolt structure 27 with resultant actuation, by the engagement of the member 35 with the cam portion 67a, whereby the audible and visual signals are put into immediate actuation; at the same time,

however, and as is better shown in Figure 6, the drop of the flag or visual signal 90, the latter being provided with a projecting lug 99, brings the latter into engagement with a switch member 100 and moves the latter into engagement with the fixed contact 101, thereby to close a circuit of which conductors 102 and 103 form a part.

Switch member 100 may be in the form of a relief spring which, with the fixed contact 101 spring 104, is insulatingly mounted in any suitable way, as is diagrammatically indicated in Figure 6 at 104, upon the inside face of the rear plate 19, any suitable means (not shown) being provided to insulatingly carry the conductors 102 through the plate 19 or through the door, from which they may be expanded to any suitable point, as is illustratively about to be described.

The contact spring 100 is sufficiently light to be brought into and held in engagement with the fixed contact 101 by the lug 99 and the weight of the flag 90, restoration of the latter as above described, as by way of the handle or knob 92 (Figure 4), removing the lug 99 from engagement with the circuit-closing switch and thereby restoring the circuit 102-103 to normal condition. Of course, it will be recalled that the knob 92 for such restoration purposes can be actuated only from the inside of the door.

The conductors 102-103 lead to any desired or suitable and appropriately located signal device which may be, for example, visual or audible or both, and where a number of doors, such as in office buildings, apartment buildings and the like, are to be monitored in accordance with my invention, the conductors 102-103 (duplicated, of course, for each door) preferably lead to a central station or central signaling station as is generally indicated at 105 in Figure 6.

The station 105 may be in the form of an annunciator provided with as many drops or signals S1, S2, S3, etc., as there are doors or door locks to be monitored. The station 105 may also include an audible signal diagrammatically indicated at 106 so connected with a suitable source of current 107 and with the windings of the drops S1, S2, etc., (substantially as shown in Figure 6) that, when the switch 100-101 of any door, for example, the door mechanism shown at the right in Figure 6, or duplicated door mechanisms only two of which are diagrammatically indicated in Figure 6 at 108 and 109, the corresponding visual signal or drop S1, S2, as the case may be, as well as the audible signal 106 is actuated, remaining actuated so long as the switch 100-101 of the particular door mechanism remains in actuated position. Accordingly, I am enabled to give an alarm at a central point or station, the alarm identifying the location of the lock mechanism being tampered with so that thereby whatever is necessary to be done may be done.

Under certain circumstances it may be desired that the action of bolt 27 be in directions the reverse of those pointed out above. For example, if door 10 is hinged to swing oppositely from the direction of swing indicated in the drawings, bolt 27 should slide to the right to assume its locked position in contra-distinction to its locking action as described above. To provide for this reversal, bolt 27 is so constructed that it may be lifted bodily and turned over in order that plate 30 thereof is uppermost and plate 29 is borne by plates 22, 45 and 46 (Figures 2 and 3). As casting 24 is also reversible, opening 26a therethrough

may be registered with bolt 27 and the operation will be substantially similar to that pointed out above with the exception that crank pin 54 now bears against arm 36 to operate the bolt and cam 5 35b on stop 35 bears against a lug 67d substantially similar to lug 67a to operate the signals when the lock is being forced.

Thus it will be seen that there has been provided in this invention a lock mechanism in which 10 the various objects hereinbefore set forth, together with many thoroughly practical advantages, are successfully accomplished. It will also be seen that the lock is simple and inexpensive in construction, versatile through its reversibility, 15 practical in operation, reliable in its sturdiness and an efficient safeguard through its signaling devices. Moreover, the lock is further characterized by space-saving compactness in proportion to its size, which facilitates ready installation.

20 As many possible embodiments may be made of the above invention, and as many changes might be made in the embodiment set forth above, it is to be understood that all matter hereinbefore described or shown in the accompanying drawings is to be interpreted as illustrative and not in a limiting sense.

I claim as my invention:

1. In lock construction, in combination, a two-part casing having a base portion provided with 30 means for slidably guiding a bolt beyond either of two opposed ends of said base portion, a bolt slidably carried by said base portion and capable of being reversed end for end and to coact with said guiding means for projecting movement beyond either of said ends of said base portion, and closure means for completing the casing and for enclosing said bolt, said closure means being provided with an apertured end wall and a closed end wall each adapted to coact with either of said 40 ends of said base portion depending upon whether or not said closure means is reversed end for end to correspond with the position given said bolt, and means for securing said closure means and said base portion together.

45 2. A lock construction as claimed in claim 1 in which said closure means carries means operable from the exterior thereof for controlling the projection or retraction of the bolt, and in which the bolt is provided with means to coact therewith in either of the two positions that may be given the bolt.

50 3. A lock construction as claimed in claim 1 in which the base portion is provided with means to coact therewith in either of the two positions that may be given the bolt.

55 4. In lock construction, in combination, a casing having slidably mounted therein a bolt made up of two separate outer sheet metal members provided with means for holding them together and 60 in spaced relation, and auxiliary bolt means positioned between said sheet-like members and provided with means for movably mounting said auxiliary bolt means for movement relative to said spaced members, and mechanism carried by said 65 casing for successively actuating said two bolt means.

5. In lock construction, in combination, a casing having slidably mounted therein a bolt for projection into the opening in a keeper wall, said 70 bolt having means capable upon actuation to engage in back of the keeper wall to prevent movement of said bolt out of said keeper opening, said bolt having a recess and said casing rotatably carrying means having a crank pin engageable in 75 said recess for thereby projecting or withdrawing

said bolt, a stop related to said casing, a detent movably carried by said bolt for coaction with said stop, a member movably carried by said bolt and having a portion positioned in the path of movement of said crank pin as the latter moves relative to said bolt recess, and operating connections between said member and said first-mentioned means and said detent for effecting actuation of said first-mentioned means and said detent in response to actuation of said member by 10 said crank pin.

6. In lock construction, in combination, a casing having slidably mounted therein a bolt for projection into the opening in a keeper wall, said bolt having means capable upon actuation to 15 engage in back of the keeper wall to prevent movement of said bolt out of said keeper opening, said bolt having a recess and said casing rotatably carrying means having a crank pin engageable in said recess for thereby projecting or 20 withdrawing said bolt, a stop related to said casing, a detent movably carried by said bolt for coaction with said stop, said first-mentioned means having an extension positioned in the path of movement of said crank pin as the latter 25 moves relative to said bolt recess for thereby effecting actuation of said first-mentioned means, and operating connections between said extension and said detent for effecting actuation of the latter in response to actuation of said extension 30 by said crank pin.

7. In lock construction, in combination, a casing having slidably mounted therein a bolt for projection into the opening in a keeper wall, said bolt having means capable upon actuation to engage in back of the keeper wall to prevent movement of said bolt out of said keeper opening, said bolt having a recess and said casing rotatably carrying means having a crank pin engageable in said recess for thereby projecting or withdrawing said bolt, a stop related to said casing, a detent movably carried by said bolt for coaction with said stop, said first-mentioned means comprising an auxiliary bolt-like member having an extension positioned in the path of movement 40 of said crank pin as the latter moves relative to said bolt recess, means pivotally mounting said bolt-like member to said bolt, and operating connections between said pivoted bolt-like member and said detent for effecting actuation of the latter in response to actuation of said extension 45 by said crank pin.

8. A construction as claimed in claim 7 in which said operating connections comprise a rotary member carried by said bolt and interposed between said pivoted bolt member and said detent, and means for effecting rotary movement of said rotary member in response to pivoting movement of said pivoted bolt member.

9. A construction as claimed in claim 7 in which said operating connections comprise a rotary member carried by said bolt and interposed between said pivoted bolt member and said detent, and means for effecting rotary movement of said rotary member in response to 60 pivoting movement of said pivoted bolt member, said rotary member having a bolt-like extension which, in accordance with the direction of rotary movement of said rotary member, is moved into or out of position in back of said keeper wall.

10. In lock construction, in combination, a casing having slidably mounted therein a bolt for projection into the opening in a keeper wall, two members pivotally mounted on said bolt and having respectively bolt-like extensions capable upon 75

actuation to engage in back of the keeper wall to prevent movement of said bolt out of said keeper opening, means operatively connecting said two members whereby actuation of one is transmitted to effect actuation of the other, bolt-actuating means carried by said casing and operating connections therebetween and said bolt and at least one of said two members for effecting proper sequential actuation thereof, stop means, detent means for coaction with said stop means, and operating connections between one of said members and said detent means.

11. In lock construction, in combination, a casing having slidably mounted therein a bolt for projection into the opening in a keeper wall, two members pivotally mounted on said bolt and having respectively bolt-like extensions capable upon actuation to engage in back of the keeper wall to prevent movement of said bolt out of said keeper opening, means operatively connecting said two members whereby actuation of one is transmitted to effect actuation of the other, bolt-actuating means carried by said casing and operating connections therebetween and said bolt and at least one of said two members for effecting proper sequential actuation thereof, stop means carried by said casing, detent means movably mounted on said bolt, operating connections between one of said members and said detent to effect actuation of the latter in response to movement of said bolt-operating means, and spring means connected between one of said members and said detent means for effecting a spring-biasing of both of said members and of said detent means.

12. In lock construction, in combination, a two-part casing having a base portion provided with means for slidably guiding a bolt beyond either of two opposed ends of said base portion, a bolt slidably carried by said base portion and capable of being reversed end for end to coact with said guiding means for projecting movement beyond either of said ends of said base portion, said bolt having means projectable laterally thereof in back of the wall of a keeper through whose opening the bolt is projected, and closure means for completing the casing and for enclosing said bolt, said closure means being provided with an apertured end wall and a closed end wall each adapted to coact with either of said ends of said base portion depending upon whether or not said closure means is reversed end for end to correspond with the position given said bolt, said bolt having means projecting therefrom and positioned thereon at such a point that, when said first-mentioned projectable means is projected in back of the keeper wall, it is spaced from said end wall, thereby to provide limited movement of said bolt along said guiding means and beyond such position in which said first-mentioned projectable means engages in back of said keeper wall; and means for securing said closure means and said base portion together.

13. In lock construction, in combination, a casing having slidably mounted therein a bolt for projection into the opening in a keeper wall, said bolt having means capable upon actuation to engage in back of the keeper wall to prevent movement of said bolt out of said keeper opening, operating means for projecting said bolt into the keeper opening and for actuating said first-mentioned means to engage in back of the keeper wall, detent means and coacting stop means, means for actuating said detent means to coact

with said stop to prevent withdrawal movement of said bolt upon completion of the projection thereof as aforesaid, and stop means carried by said bolt for coaction with said casing but positioned so as to permit a certain limited sliding movement of said bolt beyond its projected position as aforesaid. 5

14. In lock construction, in combination, a casing having slidably mounted therein a bolt for projection into the opening in a keeper wall, 10 said bolt having means capable upon actuation to engage in back of the keeper wall to prevent movement of said bolt out of said keeper opening, said bolt having a recess and said casing rotatably carrying means having a crank pin engageable in said recess for thereby projecting or withdrawing said bolt, a stop related to said casing, a detent movably carried by said bolt for coaction with said stop, a member movably carried by said bolt and having a portion positioned 20 in the path of movement of said crank pin as the latter moves relative to said bolt recess, operating connections between said member and said first-mentioned means and said detent for effecting actuation of said first-mentioned means and said detent in response to actuation of said member by said crank pin, said member having a projecting stop portion positioned with respect to said casing but so that, upon completion of projection of said bolt, the latter may partake 30 of a certain limited additional movement relative to the casing in bolt-projecting direction. 25

15. In lock construction, in combination, a casing having slidably mounted therein a bolt for projection into the opening in a keeper wall, 35 said bolt having means capable upon actuation to engage in back of the keeper wall to prevent movement of said bolt out of said keeper opening, said bolt having a recess and said casing rotatably carrying means having a crank pin engageable in said recess for thereby projecting or withdrawing said bolt, a stop related to said casing, 40 a detent movably carried by said bolt for coaction with said stop, a member movably carried by said bolt and having a portion positioned in the path of movement of said crank pin as the latter moves relative to said bolt recess, operating connections between said member and said first-mentioned means and said detent for effecting actuation of said first-mentioned means and said 45 detent in response to actuation of said member by said crank pin, said detent and stop coacting, upon completion of projecting movement of said bolt, to prevent withdrawal movement of said bolt while permitting a certain limited additional 50 movement in bolt-projecting direction of the bolt relative to said casing. 55

16. In lock construction, in combination, a casing having slidably mounted therein a bolt for projection into the opening in a keeper wall, said 60 bolt having means capable upon actuation to engage in back of the keeper wall to prevent movement of said bolt out of said keeper opening, said bolt having a recess and said casing rotatably carrying means having a crank pin engageable in said recess for thereby projecting or withdrawing said bolt, said crank pin having a range of movement such that, upon completion of projecting movement of said bolt and of said 65 first-mentioned means it withdraws from said recess, said bolt carrying stop means for coaction with a stationary part related to said casing but spaced therefrom to permit a subsequent additional movement of said bolt in bolt-projecting direction. 70 75

17. In lock construction, in combination, a casing having slidably mounted therein a bolt for projection into the opening in a keeper wall, two members pivotally mounted on said bolt and having respectively bolt-like extensions capable upon actuation to engage in back of the keeper wall to prevent movement of said bolt out of said keeper opening, means operatively connecting said two members whereby actuation of one is transmitted to effect actuation of the other, bolt-actuating means carried by said casing and operating connections therebetween and said bolt and at least one of said two members for effecting proper sequential actuation thereof, said operating connections including lost motion connecting means permitting movement of said bolt beyond its normal projected position, and stop means limiting the extent of said additional bolt movement.
18. In lock construction, in combination, a casing having slidably mounted therein a bolt for projection into the opening in a keeper wall, said bolt having means capable upon actuation to engage in back of the keeper wall to prevent movement of said bolt out of said keeper opening, operating means for projecting said bolt into the keeper opening and for actuating said first-mentioned means to engage in back of the keeper wall, said operating means including a discon-nectable connection with said bolt that becomes disconnected upon said bolt having been projected and said first-mentioned means actuated into position in back of the keeper wall, and stop means coacting between said bolt and said casing but relatively positioned to permit a certain limited additional movement of said bolt in bolt-projecting direction to take place.
19. In lock construction adapted to have associated therewith a signaling means, in combination, a casing having slidably mounted therein a bolt for projection into the opening in a keeper wall, said bolt having means capable upon actuation to engage in back of the keeper wall to prevent movement of said bolt out of said keeper
- opening, operating means for projecting said bolt into the keeper opening and for actuating said first-mentioned means to engage in back of the keeper wall, said operating means including operating connections permitting movement of said bolt beyond its normal projected position as initially determined by said operating means, whereby a separating movement between said keeper wall and casing such as would result from an attempt to jimmy the lock construction is effective to bring about movement of the projected bolt beyond its normal projected position, and means responsive to the aforesaid movement of said bolt beyond said normal projected position for controlling said signaling means, whereby, upon such a separating movement between said keeper wall and casing taking place, the aforesaid movement of said bolt beyond said normal projected position affects said controlling means and the latter effects actuation of said signaling means.
20. In lock construction, in combination, a casing having slidably mounted therein a bolt for projection into the opening in a keeper wall, said bolt having means capable upon actuation to engage in back of the keeper wall to prevent movement of said bolt out of said keeper opening, operating means for projecting said bolt into the keeper opening and for actuating said first-mentioned means to engage in back of the keeper wall, said operating means including operating connections permitting movement of said bolt beyond its normal projected position as initially determined by said operating means, whereby a separating movement between said keeper wall and casing such as would result from an attempt to jimmy the lock construction is effective to bring about movement of the projected bolt beyond its normal projected position, and stop means coacting with said bolt and said casing for limiting the extent of movement of said bolt beyond its said normal projected position.

CHARLES COURTNEY.
